ABSTRACT OF THE DISCLOSURE

Projectile having a fuze igniting a useful charge and a charge for ejecting said useful charge. The latter is connected to a braking parachute and the projectile base contains a projectile tilting charge and carries a lateral nozzle at the rear of the centre of gravity of the projectile for creating, under the effect of the gases produced by the tilting charge and ejected through the nozzle, a couple which tilts the projectile on its trajectory. Delay means are disposed between the fuze and the ejecting and tilting charges so that combustion of the tilting charge precedes ignition of the ejecting charge.

The present invention relates to projectiles of the type having a useful charge, such as an illuminating or flare charge which must be released at a point on the trajectory and then braked relative to the rest of the projectile.

In known projectiles of this type, the useful charge is usually separated from the rest of the projectile at a given point on the trajectory by means of a time fuze containing a small explosive charge of the black powder type and a clock mechanism which is set before firing the projectile. The useful charge is provided with a parachute which opens at the moment of separation and, owing to the braking action thereof, allows the useful charge to continue its descent at low speed. Now, at the moment of separation, the projectile splits up into a plurality of parts. Some of these parts are heavy and large and, in continuing on their trajectory at a speed in the neighbourhood of that of the projectile at the moment of separation, can encounter the canopy of the open parachute or the partly-open parachute so that there is a risk of tearing this canopy or preventing its opening. The base of the projectile constitutes in fact the most dangerous part for this canopy owing to its weight and position. This part of the projectile is heavy since, when firing, it must be capable of withstanding the thrust of the gases and consequently its wall is thick and strong. Further, this base carries in many cases a rear fin structure or, when it concerns a self-propelling projectile, propelling means. It must be realised that, upon separation of the useful charge and the opening of the braking parachute, the risk of the base of the projectile damaging the parachute increases very rapidly with the dimensions of the parachute and this necessitates limiting the weight of the useful load and consequently the characteristics of the projectile.

The object of the invention is to provide a projectile of the aforementioned type which remedies these drawbacks.

The projectile according to the invention is of the type comprising a time fuze for igniting the useful charge and an explosive ejecting charge adapted to eject, from the body of the projectile, the useful charge which is connected to a braking parachute, wherein the base of the projectile contains, in addition to said charge for ejecting said use-

ful charge, a projectile tilting charge and carries a lateral nozzle which is located at the rear of the centre of gravity of the projectile so as to create, under the effect of the ejection of gases produced by the combustion of said tilting charge, a couple which tilts the projectile, delay means being disposed between said fuze and said ejecting and tilting charges whereby the combustion of said tilting charge precedes the ignition of said ejecting charge.

The ignition of the time fuze therefore first produces the ignition of the useful charge and tilting charge, the projectile tilts owing to the ejection of the gases through the lateral nozzle, then the useful charge is expelled with its parachute in a direction parallel to the axis of the tilted projectile, that is, at an angle relative to the tangent to the trajectory of the projectile, and consequently the canopy of the parachute opens off the trajectory of the body of the projectile so that the latter cannot damage it.

Further features and advantages of the invention will be apparent from the ensuing description with reference to the accompanying drawings.

In the drawings:

FIG. 1 is a longitudinal sectional view of a projectile according to the invention;

FIG. 2 is a cross-sectional view taken along line 2—2 of FIG. 1;

FIG. 3 is a partial detail longitudinal sectional view of the projectile on a scale larger than that of FIG. 1, and

FIGS. 4—8 are diagrams showing the elements of the projectile in the various stages on the projectile trajectory.

In the illustrated embodiment, the invention is applied to a projectile comprising a head A, a body B, a base C and a fin structure D carried by the latter. This projectile contains a useful charge or load E which, in the presently-described embodiment, is an illuminating device or flare.

The head A of the projectile comprises a time fuze 1 containing an adjustable delay means and an explosive charge 2 of the black powder type fixed on a support 3.

The body B of the projectile comprises a cylindrical case 4 the front end of which is connected to the support 3 by shearable pins 5. This body contains the useful charge or load E consisting of a container 6 containing an illuminating charge 7 which can be ignited by the charge 2 of the fuze through pyrotechnic delay means 8.

Fixed to this container 6 by a cable 9 and suspending lines 9a (see FIG. 7) is the canopy 10 of a parachute. This canopy is disposed in an envelope consisting of two half-shells 11 and 11a and a pot 12. The half-shells 11 and 11a and the pot 12 are retained in the body 4 by a ring 13 which bears against a flange 14 on the pot and is merely a tight fit in the body 4. Screwed in this ring 13 is the front end of the base C.

The body of the projectile has an axial tube 15 which extends therethrough and transmits rearwardly the flames from the combustion of the igniting charge 2 to two rear charges 16 and 17 by way of delay apertures 18, 19.

The charge 16 can ignite, through pyrotechnic delay means 20 (FIGS. 1 and 2), a pot ejecting charge 21, whereas the charge 17 can ignite, through apertures 22, an auxiliary propelling charge 23 the ignition of which produces propelling gases which are ejected through the bore 24 of a lateral nozzle 25, after expulsion of a closing plug 26 by the pressure of said gases.

The delay means 8, 20, 22 are such that the operation of the fuze 1 and the ignition of the charge 2 at time T results, firstly, in the ignition, by way of the apertures 22, of the propelling charge 23 whose combustion lasts about 0.04 second and, then, the ignition by way of the delay means 20, of the pot-ejecting charge 21, at about time T+0.06 second, and, finally, the ignition, by way of the delay means 8, of the useful charge 7 at about time T+1 second.

The projectile therefore operates in the following manner:

At the end of time T , adjusted by the fuze, the latter ignites the charge **2**. The projectile is at P^1 on its trajectory. It is for example propelled at a speed V of the order of 200 metres per sec.

The propelling charge **23** is ignited and burns from about T to $T+0.04$ second. The gases it produce eject the lateral plug **26** and then the jet **J** of these gases (FIG. 4) gives rise to a lateral reaction force **R** located to the rear of the centre of gravity **G** of the complete projectile. The latter therefore tilts on its trajectory. At time $T+0.04$ second, the projectile has tilted to the position P^2 (FIG. 5) and its longitudinal axis then makes an angle of, for example, 30° with the tangent **T** of the trajectory. At this moment, the combustion of the auxiliary charge **23** has stopped but the projectile continues to tilt under the effect of the inertia of the impulse and reaches, at time $T+0.06$ second, the position P^3 for example inclined at 40° . At this moment, the pot-ejector charge **21** is ignited, while the speed of the projectile is still V .

This charge **21** explodes and the pins **5** shear under the effect of the pressure created and the contents of the projectile, namely the fuze **1**, the charge **E** and the parachute with its envelope (**11**, **12**) is expelled forwardly in a direction parallel to the longitudinal axis of the projectile (FIG. 6) with a speed v relative to the assembly (body **E**, base **C**, fin structure **D**) for example of the order of 10-20 metres per sec.

Within a few hundredths of a second, for example at $T+0.10$ second, the useful charge **E** has travelled through a few decimetres relative to the assembly (**E**, **C**, **D**) and the angle of tilt is then about 45° (FIG. 6).

At about $T+0.12$ second, the canopy **10** of the parachute starts to open at the end of the suspending lines **9^a**, which connect it to the charge **E** through the cable **9**, whereas the half-shells **11**, **11^a** and the pot **12** are separated therefrom (FIG. 7).

The relative disposition of the canopy **10** of the parachute and of the rear assembly (**B**, **C**, **D**) is then such (FIG. 8) that, when the parachute is completely open, its canopy is to the rear of this assembly and offset therefrom a distance a of the order of at least 30 cm. and, thereafter, said assembly of dangerous parts continues its travel at the speed V (of the order of 200 metres per sec.), whereas the charge **E** slows down from 200 metres per sec. to v —about 5 metres per sec. owing to the braking action of the parachute, there being no risk of a dangerous part encountering the parachute.

The arrangement according to the invention has therefore the following advantages:

There is no longer any risk of the canopy of the parachute being damaged by the parts **B**, **C**, **D** and the charge **E**, ignited at time $T+1$ second, descends slowly in producing the desired effect (illumination in the present case).

The device is of utility for projectiles of small calibre (60-81 mm.) since it requires very little space.

The assembly is very strong owing to the fact that the shearable pins **5** are located in the front part of the projectile, since the assembly **A**, **B**, **C**, constitutes a rigid unit.

What I claim is:

1. A projectile comprising a body having a base and, disposed in said body: a useful charge which must be released at a point on the projectile trajectory, a braking parachute connected to said useful charge, an explosive ejecting charge disposed in said base and adapted to eject from said body said useful charge, a time-delay fuze having a fuze charge communicating with said useful charge and said ejecting charge for igniting said useful and ejecting charges, said base containing, in addition to said ejecting charge, a projectile tilting charge which communicates with said fuze charge, said base including a lateral gas ejection nozzle which communicates with said tilting charge and is located to the rear of the centre of gravity of the projectile and so oriented as to eject laterally gases produced by the combustion of said tilting charge and create a moment which tilts the projectile, and delay means interposed between said fuze charge and said ejecting charge and between said fuze charge and said tilting charge and affording a delay differential which ensures that the combustion of said tilting charge precedes the ignition of said ejecting charge.

2. A projectile as claimed in claim 1, wherein said body constitutes with said base a rigid assembly and is connected in the front part of the projectile to a support of said fuze by shearable pins.

3. A projectile as claimed in claim 1, comprising an envelope for said parachute, said envelope comprising the combination of two adjacent freely disposed half-shells and a rear frustconical pot.

4. A projectile as claimed in claim 1, comprising an axial tube communicating with said fuze charge, an axial powder charge located to the rear of said axial tube and communicating with said fuze charge via said tube so that said axial tube transmits the flames produced by said fuze charge to said axial powder charge, said ejecting and tilting charges communicating with said axial powder charge through said delay means.
